By *Lawrence R. Tracy* Attorney.

UNITED STATES PATENT OFFICE.

ALFRED GEORGE BARRETT AND HUBERT HENRY BURTON, OF LEICESTER, ENGLAND.

MAT FOR VEHICLES.

Application filed November 28, 1924. Serial No. 752,789.

To all whom it may concern:

Be it known that we, ALFRED GEORGE BARRETT, a subject of the King of England, and HUBERT HENRY BURTON, a subject of the King of England, and both residents of Granby Rubber Works and Evington Valley Mills, Leicester, in the county of Leicester, England, having invented certain new and useful Improvements in Mats for Vehicles, of which the following is a specification.

Our invention relates to foot mats for the foot rests and running boards of motor cycles and other vehicles, and the invention aims to provide a molded shell of rubber or other yieldable material adapted to be mounted on the foot board of a motor cycle. On the under side of the shell are projections adapted to engage a stiffening plate over which the shell is mounted, said stiffening plate being suitably secured to the foot board. The projections on compression of the mat by the foot of a rider, under road shocks, and vibrations, will meet or bear on the stiffening plate and prevent the shell from collapsing; at the same time form cushions which enhance the shock absorbing qualities of the mat.

Reference will now be had to the drawing wherein—

Figure 1 is a longitudinal sectional view of the mat in a recessed foot board;

Fig. 2 is a top plan of the mat;

Fig. 3 is a bottom plan of the same, and

Fig. 4 is a longitudinal sectional view of a portion of the mat.

In the drawing a^4 generally designates a molded shell of rubber or other yieldable material, the wall $-a^1$ whereof constitutes

side supports and said wall is formed with an inturned flange $-a^2$ which is sprung over the edges of a metallic stiffening plate $-e$. Integral projections $-a^3$ are formed on the lower face of the mat and these projections, on compression of the mat by the foot of the rider, are adapted to meet and bear on the stiffening plate $-e$ to prevent collapse of the shell forming the mat.

$-b$ is a recessed foot board in which the mat is mounted and retained therein by nut equipped bolts $-d$. The foot board $-b$ has an upstanding heel wall and the mat has upstanding side lugs $-a^5$ that cooperate with the heel wall in forming the heel socket.

It will be noted there is a space between the foot board and the stiffening plate so that said stiffening plate may yield towards the foot board under any great strain, but in actual practice the projections $-a^3$ cushion a foot on the mat.

A foot rest for a motor vehicle comprising a recessed foot board, a mat mounted in the recess of said foot board, said mat having inturned flanges and depending projections, a stiffening plate in the recess of said foot board on the inturned flanges of said mat and supporting the depending projections of said mat so that said projections may yieldably support a foot on the mat, and side lugs carried by said mat and cooperating with a portion of said foot board in providing a heel socket.

In testimony whereof we affix our signatures.

ALFRED GEORGE BARRETT.
HUBERT HENRY BURTON.
